UNITED STATES PATENT OFFICE.

NELSON HOLMES, OF YPSILANTI, MICHIGAN.

PUMP.

SPECIFICATION forming part of Letters Patent No. 234,189, dated November 9, 1880.

Application filed March 6, 1880. (No model.)

To all whom it may concern:

Be it known that I, NELSON HOLMES, of Ypsilanti, in the county of Washtenaw and State of Michigan, have invented certain new and useful Improvements in Pumps; and I do hereby declare the following to be a full, clear, and exact description of the invention, such as will enable others skilled in the art to which it pertains to make and use it, reference being had to the accompanying drawings, which form part of this specification.

The object of my invention is to provide simple and efficient means for readily connecting and disconnecting the pump-rod respectively with a pump-handle and a windmill-pole.

The invention consists, first, in the combination, with a pump-handle provided with a pivotal sleeve and a pump-rod fitted in the latter, of a casing secured to the sleeve and a spring-pressed bolt which works in said casing and engages or disengages the handle with the pump-rod; second, in the combination, with a pump-handle provided with a longitudinal slot and a horizontal roller fitted in the latter, of a sleeve pivoted to the handle and fitted over the pump-rod and a bolt which connects or disconnects said sleeve and pump-rod; third, in the combination, with a windmill-pole provided with a sleeve in which the pump-rod fits, of a catch pivoted to the sleeve and a cam-lever adapted, by engagement with the upper arm of said catch, to throw the lower arm of the latter in or out of engagement with the notch of the pump-rod; fourth, in the combination, with a pump-rod provided with a notch and a windmill-pole having a sleeve in which the pump-rod fits, of a cam-lever pivoted to the sleeve and a catch pivoted to the sleeve, said catch having its lower extremity provided with a horizontal lug adapted to engage with the notch in the pump-rod, and its upper extremity being provided with a lug adapted to engage with the cam-lever when the latter is thrown up; fifth, in the combination, with a windmill-pole and a pump-rod detachably connected thereto, of a pump-handle detachably connected to the pump-rod and provided with a slot and a fulcrum fitted in the latter, said fulcrum and slot being adapted to permit the handle to have movement to and from the pump-rod independently

of any movement of said fulcrum; sixth, in the combination, with a windmill-pole, a pump-rod, and means for readily connecting or disconnecting the two, of a pump-handle detachably connected to the pump-rod and provided with an elongated slot and a roller-fulcrum fitted in the latter, said slot and roller-fulcrum being adapted to permit the handle to have movement in the general line of its length independently of the roller-fulcrum.

Referring to the drawings, Figure 1 is a view, in rear and side perspective, of so much of a windmill as is necessary to illustrate the invention. Fig. 2 is a view in elevation of the side not shown in the preceding figure. Fig. 3 is a detail sectional view of the device for locking the mill-pole and pump-rod together. Fig. 4 is a detail sectional view of the device for locking the pump-handle to the pump-rod.

The pump-handle A is made with a longitudinal slot, a, in which is fitted a horizontal roller, b, suitably mounted on the frame-work of the mill. This construction permits the pump-handle to be operated in connection with a straight vertical movement of the pump-rod, inasmuch as the pump-handle has longitudinal movement on its roller-fulcrum corresponding to the upward or downward stroke of the pump-rod. A sleeve, B, is pivoted to the handle and depends therefrom. This sleeve is fitted over the pump-rod and is provided with a lateral casing, c. A horizontal bolt, C, works in said casing and is adapted to engage with a hole, d, formed in the pump-rod. A spiral spring, e, is fitted over this bolt. Its inner extremity engages the bolt, and its opposite extremity has bearing against the outer end of the casing in which it works.

By partially rotating the bolt a catch, f, formed on its handle engages with the casing and maintains the bolt drawn out free from engagement with the pump-rod. When the bolt is in engagement with the pump-rod the latter is connected to the pump-handle.

In this manner the pump-handle may be readily connected or disconnected with the pump-rod, as desired.

In another application for United States Letters Patent on certain improvements in windmills, filed even date herewith, I show a pump-

rod detachably connected to a mill-pole by means similar to the above for detachably connecting the pump-handle to the pump-rod. Hence I restrict this part of my invention to the specific combination of parts herein set forth.

The upper extremity of the pump-rod fits within a sleeve, D, secured to the mill-pole. A catch, E, pivoted to said sleeve, has its upper extremity formed horizontally curved. A cam-lever, F, is also pivoted to said sleeve, the cam portion of which is adapted to engage with the curved arm of the catch and cause a horizontal lug, g, formed on the lower arm of the catch to fit in a notch, h, formed in the pump-rod.

To disengage the pump-rod and mill-pole the cam-lever is thrown up so as to cause the lever to engage with a horizontal lug, l, formed on the upper extremity of the catch. The inclined position of the cam-lever when the catch is free from the pump-rod causes the parts to be maintained in this unlocked position by the gravity of the lever. In this manner the pump-rod and mill-pole may be maintained in connected or disconnected relation, as desired.

The elongated slot in the pump-handle, combined with the roller-fulerum, permits the handle to have movement in the general line of its length to and from the pump-rod independently of any movement of the fulerum.

Having fully described my invention, what I claim as new, and desire to secure by Letters Patent, is—

1. The combination, with a pump-handle provided with a pivotal sleeve and a pump-rod fitted in the latter, of a casing secured to the sleeve and a bolt which works in said casing and engages or disengages the handle with the pump-rod, substantially as set forth.

2. The combination, with a pump-handle provided with a longitudinal slot and a horizontal roller fitted in the latter, of a sleeve pivoted to the handle and fitted over the pump-rod and a bolt which connects said sleeve and pump-rod, substantially as set forth.

3. The combination, with a mill-pole provided with a sleeve in which the pump-rod fits, of a catch pivoted to the sleeve and a cam-lever adapted, by engagement with the upper arm of said catch, to throw the lower arm of the latter in or out of engagement with the notch of the pump-rod, substantially as set forth.

4. The combination, with a pump-rod provided with a notch and a mill-pole having a sleeve in which the pump-rod fits, of a cam-lever pivoted to the sleeve and a catch pivoted to the sleeve, said catch having its lower extremity provided with a horizontal lug adapted to engage with the notch in the pump-rod, and its upper extremity being provided with a lug adapted to engage with the cam-lever when the latter is thrown up, substantially as set forth.

5. The combination, with a windmill-pole and a pump-rod detachably connected thereto, of a pump-handle detachably connected to the pump-rod and provided with a slot and a fulcrum fitted in the latter, said fulcrum and slot being adapted to permit the handle to have movement to and from the pump-rod independently of any movement of said fulcrum, substantially as set forth.

6. The combination, with a windmill-pole, a pump-rod, and means for readily connecting or disconnecting the two, of a pump-handle detachably connected to the pump-rod and provided with an elongated slot and a roller-fulerum fitted in the latter, said slot and roller-fulerum being adapted to permit the handle to have movement in the general line of its length independently of the roller-fulerum, substantially as set forth.

In testimony that I claim the foregoing I have hereunto set my hand this 24th day of February, 1880.
